UNITED STATES PATENT OFFICE.

DOUGLAS RIDER AND JOHN SIMKINS WATTS, OF LONDON, ENGLAND, ASSIGNEES TO THERMAL INDUSTRIAL AND CHEMICAL (T. I. C.) RESEARCH COMPANY LIMITED, OF LONDON, ENGLAND, A BRITISH COMPANY.

HEATING LIQUIDS BY INTRODUCTION INTO MOLTEN METAL.

Application filed February 28, 1924, Serial No. 695,757, and in Great Britain April 7, 1923.

In U. S. Patent No. 1,527,847, granted February 24, 1925 to A. McD. Duckham and J. S. Morgan, there is described an apparatus for the heat treatment of liquids by introducing them as such beneath the surface of molten metal, comprising a hood or wide-mouthed pipe constructed in such a manner that while there is a minimum of liquid present in the hood at any time, the liquid is delivered beneath the surface of the molten metal in the form of a thin stream or streams.

The present invention relates to an improvement in that described in the said specification. It has been found that as the liquid emerges from the hood and rises to the level of the molten metal fine globules of metal are thrown into the atmosphere above the molten metal, cooled and fall back as solid metal pellets. These pellets become coated with the liquid and the surface tension between the coated pellets and the molten metal is such that the pellets do not enter the molten metal again by their own weight but float on the surface of the molten metal. Consequently, the liquid flowing from the hood over the surface of the metal carries these pellets along with it. It is found, however, that if these pellets build up upon each other on the metal their weight eventually becomes such that the lower layer is immersed in the molten metal, the coating or film of liquid, which may be oil, is dispersed and the pellets melt again and enter the mass of molten metal.

The invention consists in providing means whereby the building up of the pellets is ensured. One such means consists in fitting parallel to or around the hood at a short distance therefrom a guard plate, preferably covered, the lower edge of which is immersed and the total height of which is such that when spouting occurs the fine pellets fall back in the space between the hood and the said guard plate. The liquid emerging from the hood into the space between the hood and guard plate builds up to the height of the guard plate or of a suitable slot cut in the upper part thereof and then overflows on to the surface of the molten metal beyond the plate. Any pellets formed within the space cannot be lifted by the liquid to the height of the guard plate which is sufficient to ensure that the pellets accumulate

until their total weight is such that the bottom layer being immersed in the molten metal by the superincumbent weight of the pellets, is melted as described above.

In the accompanying drawings, Fig. 1 is a vertical transverse section through part of an oil-still, provided with the improvement according to this invention. Figs. 2 and 3 are longitudinal sections on lines 2-2 and 3-3 respectively of Fig. 1.

a is a still containing molten lead, the surface of which is indicated by line b: The oil is pumped through pipe c into a long narrow, inverted box d the front wall e of which is shorter in height than the rear wall and has its lower edge serrated, the serrations being just submerged in the lead.

Co-extensive with this front wall, and of the same height, is an inverted box f considerably wider than box d and having a slot g in the upper part of its front wall.

The oil which issues through the serrations in the wall e rises to the surface of the lead within the box f where the re-melting of solidified pellets occurs in the manner described above. The oil which collects in the box over-flows through the slot g onto the surface of the lead outside the box f.

Having thus described the nature of the said invention and the best means we know of carrying the same into practical effect, we claim:

1. Apparatus for the heat treatment of liquids by means of molten metal, comprising the receptacle to contain molten metal, means for introducing the liquid beneath the surface of the molten metal contained in said receptacle, and means for preventing metal globules formed from traversing the general surface of the molten metal.

2. Apparatus for the heat treatment of liquids by means of molten metal, comprising a receptacle to contain molten metal, means for introducing the liquid beneath the surface of the molten metal contained in said receptacle, and a weir over which liquid must pass after rising to the surface of the molten metal before it can flow over the general surface of the molten metal.

3. Apparatus for the heat treatment of liquids by means of molten metal, comprising a receptacle to contain molten metal, means for introducing the liquid beneath the surface of the molten metal contained in

said receptacle, and a plate to project above the surface of the molten metal near the point at which liquid rises to the surface and situated in the path of the liquid along the surface.

4. Apparatus for the heat treatment of liquids by means of molten metal, comprising a receptacle to contain molten metal, means for introducing the liquid beneath the surface of the molten metal contained in said receptacle, a plate for isolating from the general surface of the molten metal the portion of the surface to which liquid rises and adapted to cause liquid to accumulate on the isolated portion of the surface to a depth which is not less than the height to which metal globules can build up on the surface of the molten metal.

5. Apparatus for the heat treatment of liquids by means of molten metal, comprising a receptacle to contain molten metal, means for introducing the liquid beneath the surface of the molten metal contained in said receptacle, and a plate for isolating from the general surface of the molten metal that portion of the surface to which liquid rises, said plate having an outlet for liquid at a height above the surface of the molten metal which is not less than the height to which metal globules build up on the surface of the molten metal.

In testimony whereof we have signed our names to this specification.

DOUGLAS RIDER.
JOHN SIMKINS WATTS.
